UNITED STATES PATENT OFFICE.

JAMES B. MAYBERRY, OF SHREVEPORT, LOUISIANA.

LINK CUP FOR CHAIN PUMPS.

Application filed October 9, 1923, Serial No. 667,574.

To all whom it may concern:

Be it known that I, JAMES B. MAYBERRY, a citizen of the United States, residing at Shreveport, parish of Caddo, and State of Louisiana, have invented a certain new and useful Improvement in Link Cups for Chain Pumps, of which the following is a specification.

My invention relates to a construction of link cups to be employed in chain pumps for raising liquid from wells. It is particularly adapted for use in deep wells where a strong device is necessary, but manifestly is adaptable for use in wells of any depth.

It is an object of the invention to provide a bucket link for use in chain pumps which is strong in construction and has a maximum carrying capacity.

It is also desired to provide a cup which can be easily assembled into a chain for pumping purposes and which is automatically locking when assembled.

It is also an object to so construct a link cup of the character stated that it will not become tangled when in use and which may be easily and cheaply manufactured.

Referring to the drawing herewith, Fig. 1 is a side elevation of a section of bucket chain employing my invention, certain parts being broken away for greater clearness; Fig. 2 is a side elevation taken at right angles to the view shown in Fig. 1, one link being shown in central longitudinal section; Fig. 3 is a transverse section on the plane 3—3 of Fig. 1 and Fig. 4 is a side elevation of one of the parts of my improved bucket links. Like numerals of reference designate like parts in all the views.

My invention is adapted to be employed in connection with bucket pumps, and pertains particularly to the construction of the link which forms the bucket for carrying the fluid. Such a bucket must be strong in construction and adapted to sustain a heavy weight constituting the load carried by the link itself, and in the other links below it during its progress out of the well. In the drawing I have illustrated a bucket made up of two plates, 1, identical in construction, adapted to fit together on one side thereof to provide a spherical bucket for the carrying of liquid. The plates 1 are made hemispherical at the central portion 2 forming the body of the bucket. On each end of the hemispherical central portion are formed laterally extending hooked plates 3.

These plates extend downwardly from one margin of the cup and are curved inwardly toward the central portion of the bucket to provide a hook at 4, curved to receive 60 the end of an oval-shaped link 8 therein.

One end of the bucket is intended to be presented upwardly as the chain is coming out of the well. This upper end is provided with a plurality of openings 5 there- 65 in to allow the entrance and outlet of oil or water or other fluid being pumped. Along the central vertical axis of the plates forming the bucket, the hooked end is curved or bent to one side, as shown at 6 in Fig. 3, so that the cooperating portion of the bucket may fit resiliently therein and thus automatically latch the two cooperating parts in position. In Figs. 1 and 2 the two plates making up the bucket are shown in assem- 70 bled position. The end plates 3 are bent slightly out of the plane of the central portion of the bucket at 7, as shown particu- 75 larly in Fig. 2, so that the end of the opposite engaging plate may fit against the same, causing the two ends to interlock. 80

In assembling a bucket of this kind, two plates forming the bucket are placed together with the faces of the hemispherical container contacting accurately together. A link 8 is engaged within the hooked end 4 at each end of the plate, and the parts are then rotated to cause the ends 3 to fit together so as to include the link as shown in Fig. 1. When the ends are brought together, the curved portions 6 are forced one over the other, so that they will interengage and be held resiliently in position. While the chain is extended, as shown in Figs. 1 and 2, the link 8 will assist in holding 90 the two parts of the bucket link together, and absolutely prevent the parts from becoming unlatched. 95

The two side plates making up the bucket link may be stamped out of sheet steel in large quantities, and may be made to fit accurately together so that there will be no leakage between the two parts forming the sphere. It is possible, however, to place a circular gasket or packing ring between the two plates along their contacting margins so that leakage will be absolutely prevented when the two parts are latched together. The link 8 securing two adjacent bucket links together may be formed of the usual type of link ordinarily employed in chains. It will therefore be possible to form these 100 105 110

- bucket links cheaply and supply them in large quantities to the trade at reasonable prices. The spherical form of the bucket link provides a device which will not easily be caught or hung up on other parts of the apparatus or with other links. A chain made of this form will not become tangled when it is loosened, and may be employed in the pumping operation without special 5 precaution for its safety. It is easily adaptable for use upon an operating type of sprocket wheel without danger of being injured or mutilated in its operation. It has a maximum carrying capacity and will 10 take on and discharge the liquid through the openings 5 without difficulty, and there will be little danger of loss of fluid due to movement or vibration of the chain while in use.
- 20 Having thus described my invention, what I claim as new and desire to protect by Letters Patent is:
1. A cup for chain pumps comprising a pair of coengaging plates, the intermediate 25 portions of which fit together to form a liquid container, and oppositely extending hooked ends on each plate formed to overlap and frictionally engage the hooked end of the opposite plate and to include the end 30 of an adjacent connecting link for the purpose described.
  2. A cup for chain pump comprising a pair of coengaging plates having cupped members intermediate the ends thereof, said cupped members being adapted to fit together to form a container for fluid, oppositely extending curved ends on each plate formed to frictionally engage the ends of the opposite plate, said pair of plates when 35 engaged forming openings at each end thereof to receive the adjacent connecting link.
  3. A cup for chain pumps comprising a pair of coengaging plates, the central portion of each plate being depressed outwardly 45 to form a hemispherical cup having openings in the upper end thereof, longitudinally extending ends on each plate shaped to interlock with the ends of the opposite plate whereby a central spherical container is 50 formed, the ends of plates of which are adapted to engage the adjacent link and be releasably locked thereto.
  4. A cup for chain pumps comprising a pair of coengaging plates, each plate having 55 a central curved cup member adapted to fit in fluid-tight relation with the opposite plate to form a liquid container having liquid ports therein, longitudinally extending ends on each of said plates grooved to interfit resiliently with the opposite coengaging plate, said ends forming, when said cup is assembled, a means of attachment to the adjacent connecting member in the chain.
  - 60 5. A cup for chain pumps spherical in shape, oppositely extending end plates on

said cup, said cup being divided longitudinally, said plates interfitting to latch resiliently together, and means to connect said end plates to the next adjacent cup.

6. In a chain pump, a cup formed of two 70 inter-engaging plates the central portions forming a liquid container, each end being hooked and indented whereby the plates are adapted to interlock and form an opening to receive an adjacent connecting link. 75

7. In a chain pump, a cup formed of two interengaging plates the central portions forming a liquid container, each end being hooked and indented whereby the plates are adapted to interlock and form an opening to receive an adjacent connecting link, said link acting, when said chain is in use, to hold said plates in locked position. 80

8. In a chain pump, a cup formed of two coengaging parts, the opposite ends of each part being adapted to interlock and connecting means for adjacent cups formed to also assist in locking said parts in engaged position. 85

9. In a chain pump, two cupped plates shaped to fit together to form a liquid container, inwardly hooked ends on each plate, said ends adapted, when fitted together, to receive a link, whereby said parts are locked while said pump is operating. 90

10. A cup for chain pumps formed of two interengaging parts, the body portions of said parts forming a liquid container and the ends of said parts being adapted to interlock to hold the cup parts together and to form link portions adapted to engage corresponding portions of the next adjacent connecting member. 100

11. A cup for chain pumps formed of two interengaging parts, the ends of which interlock to form a chain link, the intermediate portions of said interengaging parts forming a liquid container. 105

12. A cup for chain pumps formed of two interengaging parts, the ends of which are hooked and intended to interlock to form a chain link, the body portions of said interengaging parts forming a liquid container. 110

13. A cup for chain pumps divided longitudinally into two coengaging parts, each cup part having oppositely extending plates adapted to latch resiliently with the other coengaging plate. 115

14. In a chain pump, a combined chain link and liquid container formed of two coengaging parts, the intermediate portions of said parts, when fitted together, forming a liquid container, and the ends of each part being adapted to frictionally engage the ends of the opposite part to lock the cup parts together and form chain link members. 120

15. In a chain pump a combined chain link and liquid container having a central 125

bucket portion and longitudinal extending end plates formed in two sections adapted when fitted together to frictionally engage with each other and to include an adjacent link member.

16. A cup for chain pumps formed of two interengaging parts of semi-cylindrical form, having ports therein for passage of liquid, means to secure said parts together 10 to form a spherical container, and means to connect adjacent cups together to form a bucket chain.

17. Means for pumping deep drilled wells including an endless chain incorporating 15 therein links comprising two interengaging parts into which liquid-raising receptacles are built, the walls of said receptacles performing connecting link functions said interengaging parts being held together in 20 use by connection with adjacent links.

18. Means for pumping deep drilled wells including an endless chain incorporating combined receptacle-and-link units, each of which consists of two recessed sheet metal members joined together to form the receptacle-link.

19. Means for pumping deep drilled wells including an endless chain incorporating therein combined receptacle-and-link-units, each of which consists of two similar 30 wrought metal members recessed at their middles from which two plate-like ends extend, the plate-like ends of the two members being locked together respectively to complete the hollow bucket-link.

In testimony whereof I hereunto affix my signature this 2nd day of October, A. D. 1923.

JAMES B. MAYBERRY.
